UNITED STATES PATENT OFFICE.

GEORGE B. McCACKEN AND SAMUEL HAMER, OF WILLIMANTIC, CONN.

SPINDLE-BEARING FOR SPINNING-FRAMES.

SPECIFICATION forming part of Letters Patent No. 277,312, dated May 8, 1883.

Application filed May 20, 1882. (No model.)

To all whom it may concern:

Be it known that we, GEORGE B. McCACKEN and SAMUEL HAMER, both of Willimantic, in the county of Windham and State 5 of Connecticut, have invented a new and useful Improvement in Spindle-Bearings for Spinning-Frames, of which the following is a full, clear, and exact description.

Our improvements relate to spindle-bearings 10 for spinning-frames; and they consists in certain novel features of construction for insuring the proper support and lubrication of the spindle, as hereinafter described and claimed.

Reference is to be had to the accompanying 15 drawings, forming a part of this specification, in which similar letters of reference indicate corresponding parts in all the figures.

Figure 1 is an elevation, partly in section, 20 of a spindle, showing our improved means for supporting and lubricating the same. Fig. 2 is a plan view of the tubular bolster-support. Fig. 3 is a longitudinal section of the bolster-support. Figs. 4 and 5 are sections of the 25 spindle-bolster. Fig. 6 shows a plan and a section of a washer which is used to take the wear.

A is the spindle, provided with an extension-sleeve, B, and whirl D, as usual.

H is a base, of cast-iron provided with a nut, 30 K, for its attachment to the spindle-rail, as usual.

Q is the bolster-support, setting in a recess 35 formed in the upper part of the base H, and held in place by a cap, F, that is screwed into the base.

In the hollow stem of the base H is a plunger or stud, I, formed with a point at its upper end for supporting the bolster-support; and J is a spring beneath the plunger I, resting 40 upon a set-screw that is provided with a check-nut, R, so that the plunger is sustained.

G is a washer inserted between the bolster-support Q and the cap F to take up wear between the parts when the spindle and bolster-support are moved out of a perpendicular position by an unbalanced load. This washer 45 may be elastic or of metal; but it is not essential to the proper working of the device. When the washer is elastic it will enable the spindle 50 to adjust itself with a great degree of sensitiveness, either under a light or a heavy load.

The bolster-support Q is formed tubular

to receive the bolster C, which is firmly secured in its place by being screwed or driven in. The form or shape of this bolster, as shown 55 most clearly in Figs. 4 and 5, is tubular, with longitudinal ribs on its outer surface extending nearly to its ends; and it will be seen that its ends are shaped so that there are oil-reservoirs P at each end of the bolster, which receive the oil and prevent it from being agitated by the rotation of the spindle. The bolster is provided with notches or holes o, Fig. 4, at its lower end, to allow the outlet of oil for 60 lubricating the spindle-bearings.

The oiling is accomplished by removing the spindle and inserting a stud in its place, then filling the reservoir, removing the stud, and reinserting the spindle. This may be done 70 without loss of oil. In the working of the spindle the oil will pass down around the outside of the bolster C to the lower reservoir, and thence will work up between the spindle and bolster, so as to lubricate the bearings, the surplus passing over the top of the bolster into 75 the upper reservoir, thus making a continual circulation.

The construction shown and described allows for the self-adjustment of the spindle to 80 an unbalanced load by a very slight movement of the parts and with but little wear. It will be seen that a movement of the spindle to one side will force the shoulder of the bolster-support Q against the washer G and cap F, and by so doing the plunger I is moved downward and the spring compressed, the parts regaining their normal position as soon as the pressure is removed. The recess in the cap F 85 limits the movement of the bolster-support in a positive manner, even with a very tight band. The spindle being supported near its base, but a small movement will be made with an unbalanced load, and after once being adjusted to the degree of elasticity required the spindle 90 must necessarily remain properly adjusted for a long time, from the fact that the parts have so slight a movement. The point of the plunger I entering the bolster-support retains its central position without regard to wear, and its upward pressure will always be central.

Having thus described our invention, we claim as new and desire to secure by Letters Patent—

1. The combination of the bolster-support Q,

its supporting stud I, and means for elastically supporting said stud, with the spindle A, the bolster C, the base H, and cap F, substantially as shown and described.

5 2. The combination of the bolster-support Q, plunger or stud I, spring J, base H, washer G, and cap F, substantially as shown and described.

3. The combination, with a suitable base and

bolster-support connected thereto, of stud I, spring J, and set-screw M, substantially as described.

GEORGE B. McCACKEN.
SAMUEL HAMER.
